UNITED STATES PATENT OFFICE.

FRANK V. GARDNER, OF CINCINNATI, OHIO.

PRINTING APPARATUS.

1,321,299.

Specification of Letters Patent. Patented Nov. 11, 1919.

Application filed May 28, 1919. Serial No. 300,396.

To all whom it may concern:

Be it known, that I, FRANK V. GARDNER, a citizen of the United States, residing at Cincinnati, in the county of Hamilton and 5 State of Ohio, have invented certain new and useful Improvements in Printing Apparatus, of which the following is a specification.

My invention relates to improvements in 10 type adapted to be employed in writing designs, signs, advertisements and similar notices where only one or a few copies are required. One of its objects is to provide portable type adapted to be conveniently 15 and accurately applied by hand to produce successively the letters or elements of the design in alinement or true relation one to another. Another object is to provide for ascertaining or insuring that the letters or 20 elements are in the desired position or relation before completing the act of printing. Another object is to provide for examining 25 the printing result from each element before the element is removed, so that the printing operation may be repeated if required to secure satisfactory results. Another object is to provide an improved 30 mounting for hand operated type or design elements. Another object is to provide improved means to accurately apply large 35 hand operated type successively to produce words or designs. My invention also comprises certain details of form, combination and arrangement, all of which will be fully set forth in the description of the accompanying drawings, in which:

Figure 1 is an illustration of a partially completed sign illustrating the application of my invention.

40 Fig. 2 is a plan of one of the separate or individual type members.

Fig. 3 is a perspective view of the same.

Fig. 4 is a sectional detail on line 4 45 of Fig. 1.

Fig. 5 is a view similar to Fig. 4 illustrating a modification.

The accompanying drawings illustrate 50 the preferred embodiments of my invention, in which the respective letters of the alphabet 14 or other unit elements of the design to be printed or transferred are separately secured to backing members 15 which also have anchor blocks 16 of sub-

stantially the thickness of the letter or member 14 attached thereto. The member 14 55 may be of rubber or other flexible material or composition, as for instance the flexible composition employed by printers for inking rolls. The object is to provide letters or members 14, depending upon the size 60 thereof, which are sufficiently flexible to conform under hand pressure or such pressure as is available to the surface to be printed on, and to secure a clear sharp and uniform inked impression thereon. The 65 larger letters require to be of softer or more flexible material than smaller ones, due to the pressure available per unit surface being less.

The members 16 may be of wood, cardboard, or similar material adapted to retain 70 its position by frictional contact upon any surface with which it may be brought in contact. I preferably employ sheet cork or wood for this purpose.

The member 15 is preferably of celluloid 75 or other composition of a similar nature, and is preferably transparent or sufficiently so so that the position of the letter attached thereto and also portions of the adjoining 80 printed letter or design element may show through the member 15 and enable the operator to judge whether the letter about to be printed is in correct position or not before pressure is applied thereto. The 85 member 15 is also preferably sufficiently flexible so that the letter to be printed does not come into actual contact with the surface to be printed on until pressure is applied to member 15, and also so that the 90 letter may be lifted away from the face to be printed as indicated in dotted line Fig. 4 to examine the work, and if necessary re-ink or reprint the letter before disturbing 95 the adjusted position of the member 16 relative to the surface to be printed on. The member 15 may if desired be provided with guide lines 18 either longitudinally or transversely thereof to assist in adjusting the letter about to be printed with previously printed letters, or with reference to base lines 22 or other guide lines on the surface to be printed.

Printing in the general manner herein indicated, that is by hand using separate type 105 units, has been unsatisfactory and of limited

application, due to faulty alinement and imperfect impressions, particularly where relatively large type are employed, causing the finished work to have a staggered and ragged appearance.

5 In Fig. 5 I have illustrated a modification in which a two part sheet metal member 15' corresponding to the member 15 of Figs. 1 to 4 is employed, the two sections of said member 15' being hinged together at 20 to facilitate lifting the type member 14 to examine the work. Also if desired a continuous member of spring sheet metal might be employed, as the member 16.

15 In practice where printing is to be accomplished as in Fig. 1, a base line 22 is preferably drawn upon the surface to receive the printing matter, and if desired vertical or transverse lines 23 may also be 20 drawn on the surface to be printed. The respective members such as shown in Fig. 2 having the desired letters attached thereto are successively arranged upon the surface 24 to be printed and alined with reference to the base or other lines of the surface to be printed, and then held in place by the operator applying one hand over the section 16 to press said section firmly in contact with the surface to be printed. The 25 letter having been previously coated on its face with ink is then pressed by the other hand in contact with the surface to be printed, and may then be lifted as indicated in Fig. 4 to inspect the work before releasing the section 16 from pressure and contact with the surface to be printed. The next printing member is then alined and printed in the same manner. Should the 30 type fail to evenly cover the entire surface to be printed thereby, it may be lifted sufficiently to apply fresh ink with the finger and then the printing operation repeated without having released the member 16.

35 The apparatus herein illustrated and described is capable of considerable modification without departing from the principle of my invention.

40 What I claim is:

50 1. A set of type members each comprising a printing member having an embossed printing face, an anchor plate to be held in contact with the surface to be printed having one face substantially in the same plane with said printing face, and a connecting member to which said printing member and said anchor plate are respectively attached.

55 2. A set of type members each comprising a printing member having an embossed printing face, an anchor plate having one face substantially in the same plane with said printing face, and a connecting member through which the surface to which 60 printing is to be applied may be seen and

to which the rear face of said printing member and the rear face of said anchor plate are respectively attached.

65 3. A set of type members each comprising a printing member having an embossed printing face, an anchor plate to be held in contact with the surface to be printed having one face substantially in the same plane with said printing face, and a flexible connecting member to which the rear face of said printing member and the rear face of said anchor plate are respectively attached and which enables the printing member to be lifted from the printed impression without changing the position of the anchor plate.

70 4. A set of type members each comprising a printing member having an embossed printing face, an anchor plate having one face substantially in the same plane with said printing face, and a connecting member through which the surface to which 75 printing is to be applied may be seen, and to which the rear face of said printing member and the rear face of said anchor plate are respectively attached, said connecting member serving as a hinge to enable the printing member to be lifted from the printed impression without changing the position of the anchor plate.

75 5. A type member comprising a printing member having an embossed printing face, 80 an anchor plate to be held in contact with the surface to be printed having one face of flexible material substantially in the same plane with said printing face, and a connecting member to which the rear face of 85 said printing member and the rear face of said anchor plate are respectively attached.

85 6. A type member comprising a printing member having an embossed printing face, 90 an anchor plate having one face substantially in the same plane with said printing face, and a connecting member through which the surface to which 95 printing is to be applied may be seen and to which said printing member and said anchor plate are respectively attached.

100 7. A type member comprising a printing member having an embossed printing face, an anchor plate having one face substantially in the same plane with said printing face, and a connecting member through which the surface to which 105 printing is to be applied may be seen and to which said printing member and said anchor plate are respectively attached.

110 8. A type member comprising a printing member having an embossed printing face, an anchor plate to be held rigidly in position with reference to the surface to be 115 printed having one face substantially in the same plane with said printing face, and a connecting member to which said printing member and said anchor plate are respectively attached, said connecting member serving as a hinge to enable the printing member to be lifted from the printed impression without changing the position of the anchor plate.

120 9. A type member comprising a printing member having an embossed printing face,

an anchor plate having one face substantially in the same plane with said printing face, and a connecting member through which the surface to which printing is to be applied may be seen and to which the rear face of said printing member and the rear face of said anchor plate are respectively at-

tached, said connecting member serving as a hinge to enable the printing member to be lifted from the printed impression without changing the position of the anchor plate.

In testimony whereof I have affixed my signature.

FRANK V. GARDNER.
